US00D904986S

(12) **United States Design Patent** (10) **Patent No.:** **US D904,986 S**
(45) **Date of Patent:** **** Dec. 15, 2020**

(54) **SAFETY CONTROLLER**

(71) Applicant: **Banner Engineering Corp.**,
Minneapolis, MN (US)

(72) Inventors: **John Klesk**, Minneapolis, MN (US);
Matthew Gelineau, Minneapolis, MN (US); **Bruce Becker**, Minneapolis, MN (US); **Calvin Sargent**, Minneapolis, MN (US); **Bill Rust**, Minneapolis, MN (US); **Nathan Casteel**, Minneapolis, MN (US); **Dean Erickson**, Minneapolis, MN (US)

(73) Assignee: **BANNER ENGINEERING CORP.**,
Plymouth, MN (US)

(**) Term: **15 Years**

(21) Appl. No.: **29/696,420**

(22) Filed: **Jun. 27, 2019**

(51) LOC (12) Cl. **13-03**

(52) U.S. Cl.

USPC **D13/159**; D13/162.1

(74) Attorney, Agent, or Firm — Craige Thompson;
Thompson Patent Law

(57) **CLAIM**

The ornamental design for a safety controller, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front, top and right perspective view of a safety controller showing the new design;

FIG. 2 is a front elevation view of the safety controller of FIG. 1;

FIG. 3 is a back elevation view of the safety controller of FIG. 1;

FIG. 4 is a right side elevation view of the safety controller of FIG. 1;

FIG. 5 is a left side elevation view of the safety controller of FIG. 1;

FIG. 6 is a top plan view of the safety controller of FIG. 1; and,

FIG. 7 is a bottom plan view of the safety controller of FIG. 1.

The broken lines are for illustrative purposes only and form no part of the claimed design.

1 Claim, 7 Drawing Sheets
(7 of 7 Drawing Sheet(s) Filed in Color)
